UNITED STATES PATENT OFFICE.

HJALMAR LÖFQUIST, OF STOCKHOLM, SWEDEN.

ELECTRIC-HEATING APPARATUS.

1,012,669.

Specification of Letters Patent. Patented Dec. 26, 1911.

Application filed March 4, 1910. Serial No. 547,381.

To all whom it may concern:

Be it known that I, HJALMAR LÖFQUIST, subject of the King of Sweden, residing at 43 Artillerigatan, Stockholm, Sweden, have invented new and useful Improvements in Electric-Heating Apparatus, of which the following is a specification.

The present invention relates to electric heating apparatus, and has for its object 10 to provide such an apparatus, which will communicate a more even and comfortable heat to the rooms, in which it is placed, and which in the same time will utilize the electric energy supplied in a more economical 15 way than heretofore. For accomplishing the said objects, the apparatus is so constructed, that the heating coils are inclosed in a special casing, the walls of which are made of steatite (soap-stone), and also provided with 20 a device operated by a contact thermometer for automatically breaking the current as soon as a certain desired temperature is obtained in the apparatus or stove. In a preferred form of the apparatus, the heating 25 coils are also wound on cores of steatite, this material being known also as a good electric insulator. It has also been proved by actual tests, that the steatite is superior to most other materials concerning its capacity of storing large quantities of heat 30 and slowly delivering the same. For instance, the said steatite or soap-stone will keep the heat for about twice the time as ordinary fire-brick. The circuit-breaking 35 device operated by the contact thermometer is preferably of such a design, that it will continue to keep the circuit broken after breaking it, until the same circuit is again closed by hand.

40 In the accompanying drawing, an electric heating apparatus embodying the invention is illustrated.

Figure 1 shows the apparatus in a rear view, partly in section, Fig. 2 the same in 45 a plan view with part of the top piece broken away, Fig. 3 the said apparatus in a side view and Fig. 4 a diagram of connections.

In the example shown, the casing of the apparatus comprises a bottom piece 1, resting on wheels or rollers 2, four side walls 3, made in two pieces each, and a top piece 4, connected to the bottom piece 1 by means of clamping screws 5. The pieces 1, 3 and 4 are all made of steatite (soap-stone) and 55 provided at the joints with ribs 6 engaging grooves in the adjacent parts. The joints

between the upper and lower parts of the side walls are preferably, but not necessarily, covered by a binding metal rim 7, which may be provided with handles 8.

The bottom piece 1 is provided with shallow recesses, in the example shown six in number, for the insertion of a corresponding number of steatite cores 9 for the heating resistance coils 10. The said cores are 65 provided with spiral grooves 11 for the coils and preferably somewhat tapered upward so as to prevent the deformation or falling down of the wire constituting the coil, even when the same is elongated by the action 70 of heat. At their upper ends, the cores 9 engage recesses in a steatite slab 12 for the purpose of keeping the cores in place, which is placed at some distance from the top piece 4 for leaving spaces for signal lamps here- 75 after referred to and also has comparatively narrow clearance spaces between itself and the side walls 3. At least two of the said side walls are provided, near their upper and lower edges, with holes or ports 13 for 80 the circulation of air through the apparatus. Between the slab 12 and the top piece 4 are inserted a pair of small incandescent lamps 14 secured to the former and connected in parallel to the heating resistance wires for 85 indicating when current is flowing through the latter.

The device for automatically breaking the current when a certain predetermined temperature is reached in the apparatus comprises a contact thermometer 15 and a mercury circuit-breaker comprising a coil 16 and an armature 17 carrying a glass-tube 18 containing mercury 19 and provided with contact wires 20. The tube 18 is by gravity 95 normally held in such a position, that the mercury will cover the ends of both the contact wires 20, but when the coil 16 is energized, it will lift the armature together with the glass-tube to the position shown in 100 Fig. 1, in which action the coil may, if desired, be assisted by a spring 21. In the last-mentioned, elevated position of the glass-tube, the mercury covers only one of the contact wires 20. This position of the 105 armature 17 and the glass-tube 18 is then maintained by means of a latch 22 engaging beneath a projection 23 of the armature 17. The downward movement of the projection 23 is possible by reason of the fact that the 110 lower surface of the latch 22 is tapered or rounded off, from which it will be under-

stood that, as the projection 23 rises, it will engage the tapered surface of the latch and force the lever 24 to rotate about its pivot until the projection passes the latch, at which 5 instant the spring 26 will cause the lever to return to its normal position thus holding the projection 23 in its raised position. The said latch is carried by an angle lever 24, which can be operated by hand by means of 10 a spindle 25 against the action of springs 26, 27 so as to release the armature 17, which will then drop together with the tube 18 to its normal position.

The electrical connections between the 15 different parts of the apparatus are clearly shown in Fig. 4. From the positive main 28 the current passes through the one pole of the contact plug 29 (shown also in Figs. 1 and 2) to the main switch 30 (Figs. 1, 4). 20 Behind this switch it is divided into two portions, the greater or main portion passing to the heating apparatus proper, where it is again divided into a main portion through the heating coils 10 and a smaller 25 portion through the lamps 14. After passing through the coils and lamps these two current portions are again united to flow through the contact wires 20 and the mercury 19 of the circuit breaker and then 30 through the other pole of the contact plug 29 to the negative main 31. The smaller portion of current branched off immediately behind the switch 30 traverses a shunt resistance coil 32 and then joins the 35 main current before the latter again reaches the two-pole plug 29. From a certain part of the coil 32 a current is branched off, which passes through the contact thermometer 15 and the coil 16 and is joined again 40 to the main current before the latter has passed the circuit-breaking tube 17, so that the current through the coil 16 is broken simultaneously with the main current.

The upper contact wire of the thermometer 45 15 is placed at a height corresponding to the highest temperature allowed in the apparatus. When this temperature is reached, the mercury of the thermometer closes the current through the coil 16, which 50 will attract its armature, so that the mercury of the tube 17 leaves one of the contact wires 20. Thus, the main current is broken, and the apparatus is left to cool slowly, communicating a comfortable heat to the 55 surrounding room. As the current through the coil 16 is simultaneously broken, the armature would, however, drop again, if the latch 22 had not been engaged beneath the projection 23. Now, the armature will 60 remain in its upper circuit-breaking position, until it is released by hand, for instance when the room requires to be heated again.

The thermometer 15 is provided, in the 65 preferred construction, with comparatively

wide contact bands 33 connected to the wires, which make contact with the mercury column of the thermometer. These bands are adapted to make good contact against outer bands 34 secured to the wall 70 of the apparatus, when the thermometer is put in place. Hereby the thermometer is also made easily interchangeable if less or more heat is wanted. The switch 30, the resistance coil 32 and the circuit-breaking device are arranged in different compartments of a box 35 secured to the rear side of the heating apparatus and provided with a cover 36 (not shown in Fig. 1) for facilitating the movement of the complete stove 80 from one room or place to another. The connections between the box 35 and the stove or apparatus proper are effected by means of flexible two-wire conductors 37, 38.

Having now particularly described and ascertained the nature of my said invention, and in what manner the same is to be performed, I declare that what I claim is:

1. An electric heating apparatus for rooms, comprising heating resistance elements, walls of steatite surrounding said elements, said walls being provided with holes for the circulation of air through the apparatus a contact thermometer inside said walls, a circuit-breaking device operated by 90 said contact thermometer so as to break the current through the heating resistance elements when the temperature in the apparatus has reached a predetermined degree, and latch means for keeping said circuit-breaker device in breaking position until 95 restored to closing position by hand.

2. An electric heating apparatus for rooms, comprising heating resistance elements, walls of steatite surrounding said 100 elements, said walls being provided with holes for the circulation of air through the apparatus a contact thermometer with surrounding contact bands connected to the contacts or wires operated by the mercury 110 column, said contact bands being adapted to slide into outer bands or contacts arranged inside said steatite walls, said outer bands or contacts being connected to the heating resistance elements and to a circuit-breaking device, and latch means for keeping said circuit-breaking device in breaking position until 115 restored to closing position by hand.

3. An electric heating apparatus for 120 rooms, comprising heating resistance elements, walls of steatite surrounding said elements, said walls being provided with holes for the circulation of air through the apparatus a contact thermometer inside said 125 walls, a circuit-breaking device operated by said contact thermometer so as to break the current through the heating resistance elements when the temperature in the apparatus has reached a predetermined degree, 130

said device comprising a coil and an armature carrying contacts, a lever with a latch catching the end of said armature, when attracted by the coil, and a spring-actuated 5 spindle for moving the lever so as to cause the latch to release the armature.

In testimony whereof I have signed my

name to this specification in the presence of two subscribing witnesses.

HJALMAR LÖFQUIST.
